INVENTOR

William F. Levison

By John A. Bonnhardt

ATTORNEY.

UNITED STATES PATENT OFFICE.

WILLIAM F. LEVISON, OF CLEVELAND, OHIO.

INTAKE-MANIFOLD HEATER.

Application filed September 15, 1923. Serial No. 662,853.

To all whom it may concern:

Be it known that I, WILLIAM F. LEVISON, a citizen of the United States, residing at Cleveland, in the county of Cuyahoga and State of Ohio, have invented certain new and useful Improvements in Intake-Manifold Heaters, of which the following is a specification.

This invention is an intake manifold heater, having for an object to entirely enclose the intake manifold whereby to insulate the same against the cold air outside and to retain an unusual amount of heat within the enclosure for reasons which are obvious.

Another object is to provide a device of this character wherein the casing is so constructed as to be readily applicable to a manifold without requiring fastening means other than those commonly carried by an engine, particularly of the type used in the well known Ford automobile.

A further object is to provide a device of this character including a highly efficient heat retaining material as a packing.

A still further object is to provide a device of this character in which the parts may be stamped out and cheaply and easily formed.

It is likewise an object to provide a device of this character including means whereby an additional supply of heat may be received from the exhaust manifold.

Other objects will be in part obvious and in part pointed out hereinafter.

In order that the invention and its mode of operation may be readily understood by persons skilled in the art, I have in the accompanying illustrative drawings, and in the following detailed description based thereon, set out one possible embodiment of the same.

In these drawings:

Fig. 1 is a side elevation showing the application of my device.

Fig. 2 is an inner face view of the cover part of my device.

Fig. 3 is a similar view of the base or inner part.

Fig. 4 is a section taken on the line 4—4 of Fig. 1; and

Fig. 5 is a modification.

Having reference to the drawings throughout which similar characters of reference designate corresponding parts, this invention may be stated as comprising a casing

which entirely encloses the intake manifold I from the point of attachment to the carburetor C to the engine block E, to which it is secured by the common bridge bars B 60 found on the average engine and particularly the type used in Ford automobiles.

This casing preferably consists of two parts, the inner or base part 6 and the outer part or cover 7, which as is obvious, snugly 65 fits over the inner part 6 as shown in Fig. 4.

While modifications in the shape may of course be resorted to, it is preferable to stamp each part to substantially simulate an ordinary intake manifold, thereby including the elbow 8 which, in the base portion 6, is notched as at 9 in Fig. 3 so as to fit around the pipe connection to the carburetor. A neck 10 and the oppositely directed arms 11 having upwardly extended 70 ends 12 are provided, the ends of the base part 6 being apertured at 12' so as to permit insertion of the usual nipple 14 as shown in Fig. 4.

In attaching the device to an intake manifold, the manifold is removed, the openings in the base part are alined with and arranged over the nipples 14, whereupon the manifold is positioned in said base with its outlet openings receiving the aforesaid nipples. The cover 7 is then slipped over the base part, snugly engaging the same and entirely closing the manifold as heretofore stated.

Naturally this structure alone would not 90 greatly increase the retention of heat, and in consequence, I have sufficiently lined each section of the casing with a heat insulating material 15 consisting of a mixture of mineral wool and asbestos. This material is 95 unusually efficient in the retaining of heat in and about the intake manifold. The material forms a hard refractory packing and entirely surrounds the manifold as shown in Fig. 4.

While the structure described has proven highly satisfactory during practical tests it is probable that at times additional heat may be desired, for which reason I have arranged upon the upper face of the base part of the casing, an upstanding tube 16 opening into the casing and having its open upper end contacting with the under side of the exhausted manifold M. A widened extremity 105 16' is hooked over the exhaust manifold 110 whereby to prevent entry of foreign matter and incidently more rigidly support the

tube. As shown in Fig. 5, the cover 7 is notched at 17 so as to straddle the tube 16 for obvious reasons.

It is to be understood that the packing or heat retaining material 15 will absorb heat from the manifold and hold the same for a considerable length of time thereby insuring against refusal of the engine to start because of a cold intake manifold. The advantages are very apparent.

A very important feature is the ease with which the parts may be stamped, making an inexpensive article of manufacture. It is readily seen that there is very little labor involved in the application of the device.

Manifestly, the construction shown is capable of considerable modification and such modification as may fall within the scope of my claims, I consider within the spirit of my invention.

I claim:

1. An intake manifold heater comprising a casing entirely enclosing the manifold between the carbureter and the engine block, a heat insulating material arranged between the manifold and casing and a connection between the upper portion of the casing and the exhaust manifold for directing additional heat into the casing.
2. An intake manifold heater including a two-part casing, one part of the casing comprising a substantially T-shaped body having its front face open, and provided with an opening at each end of the T head for reception of a nipple in the charge inlet port, said

part having a cut-away portion to receive the manifold at its point of connection to a carbureter, and a second part substantially T-shaped and adapted to snugly fit over the first part.

3. An intake manifold heater including a two-part casing, one part of the casing comprising a substantially T-shaped body having its front face open, and provided with an opening at each end of the T head for 45 reception of a nipple in the charge inlet port, said part having a cut-away portion to receive the manifold at its point of connection to a carbureter, a second part, substantially T-shaped and adapted to snugly fit 50 over the first part, and an insulating material filling the space between the manifold and the casing.

4. An intake manifold heater comprising inner and outer substantially T-shaped sections, the inner section having its upper outer ends curved upwardly and provided with openings to receive the usual nipples, the lower end having a portion cut away to accommodate the curved lower end of a 60 manifold, the outer section being formed similarly to the inner section and slideable over the sides of said inner section, and into engagement with an engine cylinder block, and a heat insulating packing entirely filling 65 the space between the sections and a manifold.

In testimony whereof, I affix my signature.

WILLIAM F. LEVISON.
